UNITED STATES PATENT OFFICE.

EDWIN M. LARSON, OF LOS ANGELES, CALIFORNIA.

AUTOMATIC BUTTER-DISPENSING APPARATUS.

1,159,688.

Specification of Letters Patent.

Patented Nov. 9, 1915.

Application filed September 5, 1912. Serial No. 718,785.

To all whom it may concern:

Be it known that I, EDWIN M. LARSON, a citizen of the United States, residing at Los Angeles, in the county of Los Angeles and State of California, have invented a new and useful Automatic Butter-Dispensing Apparatus, of which the following is a specification.

This invention relates more particularly to a sanitary machine by means of which chips of butter such as are used in restaurants and hotels may be automatically cut from bars and ejected into butter plates thereby eliminating the necessity heretofore of handling the butter chips by hand during the preparation of the same for table use.

An object of this invention is to provide a machine to be operated by waiters or other attendants in restaurants, hotels or other eating places whereby chips of butter will be dispensed individually and automatically and without handling, so that the waiter or other attendant by placing the individual butter dish in position to receive the chip and then operating the machine will deliver a butter chip of the appropriate size onto the butter plate so that it may be taken directly from the bar of butter to the guest or customer in perfect sanitary condition.

An object of this invention is to provide a novel unitary machine which will automatically guide a body of material such as a bar of butter into position, cut rectangular parallel sided chips from such body and eject the cut portions into plates.

I regard this invention as pioneer, being the first machine which may be charged with one or more bars of butter and then when operated will at every operation without further attention, cut a chip of butter and eject the same into the receiving butter plate so long as the charge is not exhausted.

Further objects of this invention are simplicity, compactness, ease and convenience of charging, large capacity, convenient and proper refrigeration, and invariable appropriate performance of the necessary operations at the proper times.

It is necessary that the butter shall be kept at a proper temperature, so that it will cut properly without breaking or mashing and provision is made whereby such temperature is readily maintained.

Other objects and advantages of this invention may appear from the subjoined detail description.

Various changes of construction may be made without departing from the invention or some of the features thereof.

Referring to the drawings, the invention comprises a combination of mechanisms which will be considered in the following order: mechanism A, for cutting the butter; mechanism B, for automatically stopping the cutter centrally between the cutting strokes; mechanism C, for ejecting the butter chips; mechanism D, for connecting the cutter and ejector actuating mechanism with the butter bar advancing mechanism; mechanism E, for advancing the butter bar; mechanism F, for supporting the butter bars and moving them successively into position for coöperation with the butter bar advancing mechanism; and mechanism G, for regulating the thickness of the butter chips.

This invention includes said mechanisms and the said combination and also various parts and combinations of parts that will be more fully set forth in the subjoined detail description.

The apparatus shown is designed to be actuated by the oscillations of an operating handle, which moves right and left at the front of the machine. Provision is also made for automatically dropping the butter bar supporting tray after the same is emptied and provision is also made whereby access to the interior of the case may be had conveniently from the front to remove the empty trays and to reach the internal mechanism.

The accompanying drawings illustrate the invention, Figure 1 being on a reduced scale and the other figures on a larger scale. Fig. 1 is a front elevation of an automatic butter dispensing apparatus embodying this invention, also showing a dish in position to receive a butter chip. Dotted lines indicate hidden portions, solid lines show parts in normal stationary position, and dot and dash lines indicate positions assumed by said parts at the beginning of the right ejecting stroke. The guard is broken away to expose certain parts that would otherwise be hidden. Fig. 2 is a fragmental plan section on a larger scale common to all the views except Fig. 1 and viewed from irregular line α^2 , Figs. 1, 3 and 7; and is illustrative of the mechanisms A, B and C. Parts are shown in the chip-ejecting position corresponding practically to the position shown in solid lines in Figs. 3 and 7.

Fig. 3 is a fragmental front elevation further illustrating the mechanisms A, B and C. Solid lines show the chip-ejecting position corresponding to the position shown in solid lines in Fig. 7 and just following that indicated in dot and dash lines in Fig. 1. Broken lines indicate the position of parts after the return of the cutter at the completion of the right-hand cutting stroke, while dot and dash lines indicate normal rest position of parts. Fig. 4 is a view analogous to Fig. 3, showing in solid lines the position assumed by parts at the beginning of the left-ejecting stroke. Dot and dash lines indicate the position of parts at the completion of the left ejecting stroke and also at the beginning of the operation to advance the plunger. Fig. 5 is a view analogous to Figs. 3 and 4 showing a position assumed by the parts as the cutter is nearly back to its normal central position and the plunger actuating arms is about to drop to cause the actuating mechanism E, (see Figs. 14, 15, 16, 17) to advance the plunger. The guard is omitted from Figs. 4 and 5. Fig. 6 is a detached broken mid-sectional detail illustrating means to secure the filose cutter to the cutter slide. Fig. 7 is a fragmental elevation in broken longitudinal section planes indicated by vertical portions of irregular line x^7-x^7 , Figs. 1, 2, 3, 9, 12 and 14, viewed looking from the left side of Fig. 1. Solid lines show the ejector extended and discharging a chip of butter corresponding to the position shown in solid lines in Fig. 3. Broken lines indicate positions of the butter chip as it drops to the dish corresponding with the positions indicated in Fig. 14, while dot and dash lines indicate the position of the ejector when retracted, and also a position the hinged front member assumes when swung out. Fig. 8 is a fragmental sectional elevation on two vertical planes at right angles to each other; the left part being analogous to Fig. 7 illustrating the mechanisms D and E viewed from line x^8-x^{10} , Figs. 9, 11 and 14; and the right part being viewed from line x^8-x^8 , Fig. 14. The connection between the mechanisms D and E and the operating handle is represented diagrammatically by broken lines while dot and dash lines indicate a position the parts assume as the plunger is kicked forward to advance the butter from the position shown in solid lines preparatory to the next cutting operation. The portion shown in solid lines at the right is a rear view of parts shown in the same position from the front side in Fig. 5. Fig. 9 is a fragmental broken plan section from irregular line x^9-x^{14} , Figs. 1, 3, 7, 12, 15, and 16, looked down on from the left in Figs. 1 and 3, from the right in Fig. 12, and from the rear of Figs. 15, 16, indicating in dot and dash lines the

extended position of the plunger shown in solid lines from the other side in Fig. 16; and also showing the normal holding position of the butter lowering latch. Solid lines show the retracted position of the plunger agreeing with Fig. 15, and the extended latch about to return to the normal holding position. Fig. 10 is a fragmental mid-sectional elevation on line x^8-x^{10} , Figs. 9 and 14. Fig. 11 is a fragmental broken transverse sectional elevation viewed from irregular line x^{11} , Figs. 9, 10 and 14, showing parts in the position corresponding to Fig. 9. Solid lines illustrate a position of parts at a step in the butter-lowering operation. Dot and dash lines indicate the normal stationary position from which parts have moved to said position shown in solid lines. Fig. 12 is a fragmental broken transverse section viewed from irregular line x^{12} , Figs. 7, 8, 9, 10, 14 and 15, looking toward the front of the machine. Parts are broken away for clearness of illustration and are in the chip-ejecting position shown in Figs. 3, 7 and 14. Fig. 13 is a perspective detail of one of the butter containers viewed from the under side thereof. Fig. 14 is a broken plan section looking down from the back of the machine. The section is on irregular line x^9-x^{14} , Figs. 1, 3, 7, 12, 15 and 16. Parts are shown in the chip-ejecting position shown in solid lines in Figs. 3 and 7. Broken lines indicate different positions of the butter chip as it drops to the dish. Parts are broken away for clearness of illustration. Fig. 15 is a fragmental broken longitudinal section viewed from irregular line x^7-x^{15} , Figs. 3, 9, 12 and 14, looking in the opposite direction from that of Figs. 7 and 8, illustrating the mechanism E. The parts are shown in the position they assume when the plunger has just retracted and a full tray of butter has replaced the empty tray that has dropped to the bottom of the machine preparatory to being removed. Fig. 16 is a view analogous to Fig. 15 showing parts in the position they assume when the cutter and ejector are about to perform final operation before the plunger is retracted to the position shown in Fig. 15. The ice chest and drip pan are omitted from this view. Fig. 17 is a fragmental mid-section analogous to Figs. 7 and 8 illustrating the mechanism G. In this view the parts are adjusted to cut butter chips twice as thick as those cut by the machine in the previous views. Parts are in the position they assume when the plunger has just been released and is about to retract to the position shown in Fig. 15. The guard is omitted. Fig. 18 is a fragmental broken elevation viewed from irregular line x^{18} , Fig. 17 and is analogous to the right fragmental portion of Fig. 8. Parts are shown adjusted to secure greater

amplitude of movement of the plunger actuating arm.

The machine may be constructed of various materials and in any desired form, and as shown in the drawings embraces a case comprising a rectangular metal frame 1, a floor 12, a top 1" and lid 1", glass plates 2 at sides and back, and upper, intermediate and bottom front sections; the upper section 10 being provided with glass side panels 3 and a central swinging door 4, which is hinged between the panels 3 on a vertical axis; the intermediate section or member 5 being hinged on a horizontal axis at its lower edge 15 and capable of being swung down and out to permit easy access to the interior, and being provided with a guard 6 detachably mounted above and in front of a central front opening 7 therethrough which communicates with the interior of the case for the ejection of the butter chips.

Inside the case there is provided a space for an ice chest 8 having legs 9 to hold a supply of ice in the upper rear portion of the case to cool the case and its contents, including the charge of material to be chipped and dispensed and also the mechanism hereinafter described for supporting moving, holding and cutting said material, 30 as the butter bars 10 and 10". The bottom of the ice chest 8 is provided with holes *a*, (see Figs. 14, 15 and 17,) through which water from the melting ice may drip into a bifurcated pan 11 that rests upon the floor 35 12; said pan being provided with a faucet 13 preferably at the front of the machine to drain the pan as the ice melts. The pan is bifurcated so as to fit into the case at the rear and on both sides of the mechanism- 40 carrying frame which will be hereinafter fully described.

The guard 6 is in the form of a hood fitting over the opening through which the chips are to be ejected and extending below 45 said opening and open at the bottom only considerably below the bottom of the said opening through which the chips are to be ejected, so that the cold air will be conserved in the machine.

50 *Butter-cutting mechanism A.*—The butter bars 10, 10" are carried by the bar holders comprising trays 10"" supported by suitable means hereinafter described and adapted to successively hold their respective bars in 55 cutting position behind the central opening 7 through which the chips are to be ejected. The butter-cutting mechanism A is carried by the hinged intermediate section 5 and comprises a horizontal transverse slide 14 60 having an orifice 15 therethrough and mounted to reciprocate transversely of the machine in top and bottom guides 16 carried by and forming part of the intermediate section 5 which is hinged at the bottom on 65 a horizontal axis 17 and is held normally up-

right in closed position by the latch 18 engaging a portion of the frame 1 at the front of the case. On the inner face of said slide is mounted the cutter means, preferably in the form of an individual filose cutter 19, 70 being preferably a single wire, extending vertically across the open space 15 of the slide 14; and being detachably secured in place by suitable means such as studs 20 fixed to the slide above and below the orifice 75 15, said wire being passed through holes 21, adjacent the edges of the orifice and wrapped around said studs and stretched taut and clamped against the slide by nuts 22 screwed home upon the studs to firmly 80 hold the wire.

The transverse slide 14 is provided at one side with a vertical slot 23 transverse the slide, through which slot extends the pin 24 of a crank arm 25 that is between the intermediate member and the slide and is fixed upon one end of a stub shaft 26 which extends through and is journaled to the intermediate member 5 and is operable a half turn at a time by a crank lever 39 outside 90 the case. The crank pin 24 fits the slot which is in parallelism with the filose cutter and is equal in length to the diameter of the path of the crank pin so that a complete cycle of the slide is effected at each full revolution of the pin. 95

By opening the intermediate section 5 the butter-cutting mechanism may be dropped down out of the way as indicated in dot and dash lines in Fig. 7; thus giving free access 100 to the interior of the case from side to side across its front.

The slide 14 is arranged to normally stand at rest with the filose cutter in a vertical plane centrally of the opening 7 so that 105 whenever the butter bar is moved forward while the slide is in its normal position of rest the bar will be slit along its vertical mid-plane by the filose cutter. The mechanism which operates the slide is constructed 110 and arranged as hereinafter described to alternately move the slide from its central position of rest to one side and back to rest and then vice versa, from the point of rest to the other side and back to rest; that is to 115 say, the filose cutter normally stands at rest centrally behind the opening; and at each operation of the slide is moved by means of the slide from the center to one or the other side and back to the center where it again 120 comes to rest.

Means are operably connected and timed with the slide 14 to intermittently advance the butter bar 10" along the holder 10"" and to project one end of the butter bar step 125 by step through the orifice 15 and past the stationary filose cutter 19 at the alternate restings of the cutter, so that at each advance of the bar a longitudinal slit 27 will be cut in the bar along the vertical axial 130

plane of the bar, so that the portion 28 projecting forwardly from the holder will be cut off from the bar in the form of two chips that are severed at separate strokes independently of each other by reason of the alternate movements of the cutter from rest to the sides in first one and then the other direction, one movement of the cutter forming the chip 29 in Figs. 7 and 14 and the other movement forming the chip 30 in Fig. 4.

Mounted upon the front of the hinged intermediate section 5 at each side of the opening 7 are slotted slides 31 provided with abutments 32 adapted to extend into said opening 7 in position to support the sides of the forwardly projecting portion 28 of the butter bar 10", thereby affording gripping means to hold the forwardly projecting portion 28 of the butter bar against displacement under pressure of the filose cutter 19. The abutments 32 are adjustably secured in place upon the member 5 by means of screws 33 extending through slots 34 in said abutments and screwing into said member 5. The filose cutter is adjacent to the abutments, being fastened just far enough back to be out of alignment with the rear edges of the same.

The stub shaft 26 (see Figs. 14 and 1 to 5) is fixed by pin 25' at its inner end to the crank 25 and is mounted in a bearing 35 fixed to and projecting from the front of the hinged member 5; and upon the outer end of said shaft there is secured by pin 26' a collar 36 provided with two oppositely-arranged ratchet teeth 37 adapted to be alternately engaged by a spring-controlled pawl 38 carried by the operating crank lever 39 that is hand operated in the direction of the solid curved arrows in Figs. 3 and 4, and is returned, in the direction of the broken curved arrow in said Fig. 3, by a spring 40 that is fixed at one end to the hinged section 5 and is coiled around the bearing 35 inside the housing or crank drum 41 and secured at the other end to the crank lever 39 (see the dotted construction in Fig. 2) to return it to rest position against a stop 46 whenever the crank lever is released after being operated to turn the crank 25 to move the slide in either direction. The ratchet roller 42 in the pocket 43 prevents backward rotation of the shaft 26 and crank 25.

The bars to be cut are twice as wide as they are thick and to cut them into squares of any desired thickness it is only necessary to move the filose cutter from and to its central station alternately right and left each stroke from and return to rest serving to sever a chip of a thickness determined by the depth to which the cutter enters the bar when the bar is advanced.

Mechanism B.—The mechanism B for au-

tomatically stopping the cutter is illustrated in Figs. 1 to 5 and Figs. 7, 12 and 14. The cam 44 on the crank drum 41 actuated by the crank lever 39, actuates the rock shaft arm 45 at the end of the return stroke of the operating crank lever 39 as said lever returns to normal upright position against the stop pin 46 as shown in Fig. 1; the rock shaft 47 to which said arm is fixed being journaled in the member 5 and operatively connected inside said member with two oscillating bars 48, 49, that are connected together by a connecting rod 50, moves said bars simultaneously in reverse directions; the bar 48 being fixed near one end to the rock shaft 47 and provided with a stop face 51 at the end of its long arm, and pivoted at the short arm by a pivot 52 to the connecting rod 50, while the lower oscillating bar 49 is provided with a stop face 53 almost vertically below the stop face 51 and facing in the direction opposite thereto. The pin 54 connecting the rod 50 to the lower bar 49 is between the stop face 53 and the pin 55 which pivots said lower bar to the intermediate section 5; and the pins 52 and 54 are equidistant from the centers on which said bars oscillate, while the faces 51 and 53 are practically equidistant from such centers, so that when the rock shaft 47 is operated the stop faces are moved up and down practically the same distance though in reverse directions.

The weight of the rock shaft arm 45 and oscillating bar 48 overbalances that of the oscillating arm 49 and connecting rod 50, so that when the rock shaft arm 45 is unsupported by the cam the stop face 53 is raised into the way of the pin 24 in its movement from right to left in Fig. 1 and the stop face 51 is lowered into the path of said pin as it moves from left to right. Consequently by this means when the operating crank lever 39 is fully depressed to the dash line position shown in Fig. 3 the pin 24 engages the lower stop face 53, thus stopping the operating crank lever 39 which is thereupon returned by the spring 40 to the stop 46 at which point the rock shaft arm 45 is again lifted by the cam 44, so that at the next right movement of the operating crank lever 39 the crank pin 24 is allowed to move onward; and as it moves, the cam 44 is again withdrawn from the rock shaft arm 45 whereupon the weight of the overbalancing parts drops the stop face 51 into the way of the crank pin 24 which is thereby stopped when the crank pin reaches the position vertically above that at which it was stopped by the face 53. It is thus seen that at each full right movement and depression of the operating crank lever, the slide is moved to carry the filose cutter from mid-position to one side and return to mid-position; the normal stoppage of the slide

and the cutter it carries always occurring at the mid-position.

It is to be noted that the means for relatively moving the cutter and the butter bar 5 are so constructed as to constitute, in each instance, means to cause relative direct, non-pivotal movement between the cutter and the butter bar, thus to form the usual butter chips having parallel flat sides.

10 *Mechanism C.*—The mechanism C for ejecting the butter chips is illustrated in Figs. 1, 2, 3, 4, 5, 7, 15, 16 and 17. The ejector comprises a sleeve 56 having an actuating pin 65 and ejecting finger 66 that 15 is slidably and rotatively mounted between stops 57, 58 upon a guide-rod 59 that is carried by the intermediate section 5 and that extends parallel with and adjacent to the slide 14; said guide-rod being preferably 20 mounted in said stops which are fixed to the front of the hinged intermediate front section 5. Ejector actuating tappets 60, 61 provided with downwardly diverging faces 62, 62' and horizontal slots 63 are fixed to 25 the slide by screws 64 passing through said slots and, when the screws are loosened, are adjustable toward and from each other along the slides. The actuating pin 65 extends between the faces 62, 62', and a spring 30 67 in the form of a spiral loop is bent around the ejector sleeve, one loop end of the spring being under the actuating pin 65 and the other loop end resting against the slide 14, so that the upward pressure of the spring on 35 the pin retracts the ejecting finger. Said spring yieldingly holds the vertical tip 68 of the ejecting finger in a vertical transverse plane that extends just in front of the filose cutter. As the slide 14 moves to the right 40 the tappet face 62 engages the actuating pin 65 and slides the ejector along the rod 59 until the end of the ejector sleeve 56 impinges against the block 58, which thereupon holds the ejector against further lateral movement while the oblique tappet face 45 62 continues to move to the right thereby forcing the actuating pin down and overcoming the resistance of the spring 69 and throwing the ejecting finger and the tip 68 forward. The result of this operation is 50 that the ejecting tip 68 runs along the top of the rear side of the butter chip just in front of the filose cutter until said chip is severed and then said tip moves outward 55 to eject the chip. On the return movement of the sleeve toward the left the ejector slide remains momentarily stationary on the guide rod 59, while the filose cutter passes the ejector tip. When the tappet face 62 60 has receded from the actuating finger the spring 69 returns the ejector tip to its retracted position, and then the tappet face 62' engages said pin and slides the ejector along the guide rod behind the filose cutter; 65 and upon the next actuation of the slide the

tappet face 62' moves the ejector along with its tip just behind the filose cutter, and when the sleeve engages the block 57, the tappet face 62' and the ejector act practically as just described with relation to the tappet face 62; thus ejecting the chip severed from the left side of the bar. By this arrangement the ejecting thrust of the finger upon either of the butter chips 29 or 30 occurs at the top and near the upper outside corner, 75 thus directing the chip forwardly toward the butter plate 70 which is placed centrally under the guard 6 upon an extension of the floor 71 that forms the butter plate shelf.

The timing of the ejecting mechanism 80 with relation to the cutting mechanism may be accomplished by the adjustment of the slotted tappets transversely along the slide 14 upon their screws 64.

Mechanisms D, E, F and G are mounted 85 inside the case upon the frame 72 that is fixed to the floor and to the front portion of the frame of the case by screws 72', and that comprises two front and two rear standards 73, 74 and top and bottom 90 braces 75.

95 *Mechanism D.*—The mechanism D for connecting the cutter and ejector actuating mechanism with the butter bar advancing mechanism comprises a rigid rock-shaft arm 76, arranged in operable relation to the crank-pin 24, and mounted on a rock-shaft 77 that is journaled to the front and rear standards 73, 74 and that is connected by an arm 78 and a connecting rod 79 with 100 one end of a pivoted lever 80 that is pivotally mounted at 81 upon the rear extension 82 of the frame 72; the other end of said lever 80 being connected by a connecting rod 83 with a ratchet arm 84 that is journaled on a transverse driving shaft 85 and is provided with a spring-pressed driving pawl 86 which engages a ratchet wheel 87 fixed on said shaft to turn the shaft the space of one or more notches of the ratchet 110 wheel at each complete revolution of the crank-pin 24. The spring-pressed locking pawl 88 pivoted at 89, underneath the ratchet-wheel 87, to the extension 82 prevents back movement of the ratchet wheel. 115

120 As the rock-shaft arm 76 is operated by the crank-pin 24 the pawl 86 is retracted from the ratchet wheel, and in order to drive the pawl 86 and the butter bar advancing mechanism E, spring means 90 are arranged to be compressed and released by each operation of the rock shaft; the entire action of said spring means occurring as the crank-pin 24 passes the rock-shaft arm 76.

125 It is desirable that the spring means shall be of considerable strength in order to move the butter bar and overcome the force of the means that returns the bar advancing means to initial position, and to make its action to advance the butter bar positive and certain. 130

To this end lost motion connecting means are provided whereby the spring 90 may be compressed at a determined period as the crank-pin 24 actuates the rock-shaft arm 76, 5 and which connecting means under the action of the spring will suddenly actuate the pawl 86. Said means comprise the driving lever 91 fulcrumed at 92 to the frame extension below the lever 80 and provided 10 with a roller 93 between the fulcrum 92 and the point at the end of the lever 91 on which the spiral spring 90 acts through the knife-edge bearing 93'; said spring being held in place by a spring holder formed by a rod 15 94 run through the bearing and the spring, and a tension nut 95 on said holder.

It will be seen by reference to Figs. 7 and 8 that on the upstroke of the connecting rod 79, the pawl 86 is retracted and as the roller 20 93 is acted on by the lever 80 the free end of the lever 91 and the washer 93' are raised thereby compressing the spring 90; and that as soon as the crank-pin 24 has passed the rock shaft arm 76 the spring 90 25 at once acts to operate the lever 91 and the pawl is thereby advanced to drive the ratchet wheel and rotate the driving shaft.

The lower portion of the spring holder 94 is curved in an arc described from the fulcrum 92 of the lever 91 so that the end of said lever may run freely up and down said guide to compress the actuating spring and to respond thereto.

The driving shaft is connected to drive the 35 mechanism E for advancing the butter bar.

Mechanism E.—The mechanism E for advancing the butter bar comprises a mutilated gear 96 fixed to the shaft 85 and engaging a rack 97 fixed to the plunger 98 having the 40 adjustable butter advancing plates 99, 99' mounted at the forward end thereof and separated by a narrow open space forming a cutter-way 100 to allow the plates to pass one step beyond the filose cutter after the 45 last chips have been scraped from the plates and ejected from the machine. The toothed segment 101 of the mutilated gear 96 is of sufficient length to move the slide forward its full length at each revolution of the mutilated gear to carry the bar-advancing plates one step beyond the filose cutter; and the blank segment 102 of said gear 96 is of sufficient length to disengage the rack and allow it to run freely back at the end of 55 each revolution of the gear.

The butter moving plunger 98 is mounted in a horizontal guide-way 103 provided with a standard 104 to support the rear end of the plunger retracting spiral spring 105, the 60 front end of which is connected by a standard 106 with the slide.

The locking pawl 88 is constantly in position to prevent back movement of the ratchet wheel driving shaft 85 and the mutilated 65 gear 96; and it is necessary that the mu-

tilated gear shall not be allowed to revolve forward during the retraction of the bar advancing rack 97. With this end in view a latch 107 is pivoted to the frame extension 82 and is operated by a spring 108 to engage 70 a catch in the form of a pin 109 that projects from the mutilated gear in position to engage the latch shoulder 110 when the blank segment 102 of the mutilated gear is adjacent to the rack 97, so that at that time 75 the mutilated gear is held from back action by the locking pawl 88 and from forward action by the latch 107.

A tripper in the form of a pin 111 fixed to the rack, projects into the way of the 80 latch 107 to retract said latch from the catch pin when the rack is fully retracted. A rack-starter in the form of a finger 112 fixed to and revolving with the mutilated gear extends to engage the starting shoulder 85 113 on the rack, when the tripper has released the latch so that on the next forward movement of the pawl 86 the rack will be advanced to engage the toothed segment 101.

The machine is intended to chip, in succession, a number of butter bars; and with the object of allowing the successive bars to be fed vertically, provision is made whereby the butter-advancing plunger shall be supported wholly by means outside the space 95 either above or below the butter bar carrier. With this object in view the slide-way 114 of the frame extension is extended rearwardly the full length of the plunger, and is slotted longitudinally with parallel side 100 slots 115 and an intermediate toothed slot 116. On the slide-way 114 is mounted an auxiliary slide 117 on which is mounted the plunger slide 118 that carries the rack and is provided with parallel slide slots 119 and 105 an intermediate toothed slot 120. The teeth 121 of the intermediate slot 116 are on one side of their slot, and teeth 122 of the slot 120 are on the other side of their slot, and a stub shaft 123 is journaled in the auxiliary slide 117 and is provided at its opposite ends with pinions 124, 125 to engage the teeth of the intermediate slots respectively, so that as the plunger slide is advanced, the auxiliary slide is advanced at half the speed, 110 and vice versa; thus operating to keep the auxiliary slide on the guide to support the plunger slide when it is moved into the way of the butter bars.

Retaining blocks 126 are fixed to the auxiliary slide and run in the slots 115 in which they are dove-tailed to hold the auxiliary slide in place on the slide-way. Other retaining blocks 127 are in like manner fastened to the auxiliary slide and dove-tailed 125 in the slots of the plunger slide.

By this construction the plunger is capable of forward extension the full length of the butter bar and is yet firmly supported by the rear extension of the frame which does 130

not project into the way of the butter bar or the carrier therefor.

The guide bar 127' fixed to the rear frame extension extends over the edge of the plunger slide to hold it from drooping as it is shoved forward.

Mechanism F.—The mechanism F for supporting the bars of butter and moving them successively into position for co-operation with the butter bar advancing plunger comprises four bracket carrying sprocket chains 128 mounted in pairs on pairs of sprocket wheels 129, 129' on opposite sides of the butter bar way 130. The brackets 131 on said chains are arranged at intervals apart somewhat greater than the thickness of the butter bars to be chipped, and butter-bar supporting trays are provided according to the number of superposed butter bars 20 that can be accommodated at one time in the butter way. The upper sprocket wheels 129 are mounted on driving shafts 133 that are journaled to the frame 72 and said shafts are connected by gearing 134, 135, 136, 137 to 25 rotate at the same speed, said gearing being fixed to the frame 72. The lower sprocket wheels 129' on one side of the frame are fixed on a shaft 138 that is journaled to said frame, and an escapement wheel 139 provided at intervals on one side with teeth 140 is fixed to the end of said shaft. An escapement lever 141 is pivoted at 142 to the bracket 143 on the rear frame extension and is normally held by the spring 144 in the 30 way of said teeth to support the escapement wheel against the weight upon the brackets. The upper end of the escapement lever 141 is provided with a front oblique face 145 extending into the way of a tappet 146 that is pivoted to the plunger slide and is held by a spring 147 against the forward stop 148 on 35 said slide, so that when the plunger returns on its backward stroke the tappet will engage the escapement lever and momentarily withdraw it from the tooth of the escapement wheel with which it is engaged and allow the load of the brackets to move the sprocket chain and wheels, thus lowering the empty tray out of the way and the next 40 tray above into position with the butter bar aligned with the plunger and central opening 7. The escapement lever is normally held oblique to the plane of the escapement wheel, so that when its upper limb is in position to 45 intercept a tooth its lower limb is withdrawn from the way of the teeth; and said lever is arranged in a common plane with a lower chord of the escapement wheel. The escapement teeth are beveled on their ascending faces to engage the underside of the lower 50 end of the lever should said lever fail to return to its normal position by the action of the spring 144 after being withdrawn by the tappet 146, thereby to insure swinging the 55 lever to move its upper end into the way of 60

the tooth immediately following the one the upper end of the lever has just escaped, thus to insure stoppage of the escapement wheel as each tooth reaches the upper limb of the escapement lever.

The teeth are spaced on the escapement wheel a distance apart sufficient to allow the sprocket chain to move the space between two brackets, so that when the escapement lever is thrown off to release a tooth, its upper limb is immediately returned at the close of the backward stroke of the tappet by the spring 144 into the path of the next tooth. Consequently, whenever the escapement lever is tripped by its tappet, the butter bars 70 and their supporting trays are allowed to descend just far enough to bring the lowermost butter bar into the way of the plunger. 75

The brackets are arranged on the sprocket chains in such position relative to the operating parts that when the sprocket chain is stopped a set of brackets are in position to support the butter bar and tray on a level with the filose cutter and the opening 80 through the intermediate hinged section of the case, so that the butter bar will be supported in the path of the plunger ready to be forced through said opening as the plunger is advanced step by step.

The butter bar holder 10''' comprises a tray 149 formed of a plate having ears 150 bent up at its rear end to hold the rear end of the bar and provided with butter bar guides 151 at the front end to direct the bar into the path of the filose cutter. Said guides are adjustable being provided underneath the plate with arms 152 pivoted to the plate at 153, 153' and provided at their ends with intermeshing segments 154 so that 85 when the guides are spread apart they are at an equal distance from the longitudinal midline of the plate. These guides are spread apart whenever it is desired to place a bar of butter in the tray and are then pressed against the sides of the bar of butter, thereby holding said bar in true alinement so as 90 to readily pass between the lips 32.

Mechanism G.—The mechanism G for regulating the thickness of the butter chips comprises means for changing the position of the rock shaft arm 76 and for this purpose a movable bearing 155 is slidably mounted on one of the upright front standards 73 and is provided with a portion 156 to engage the under side of the arm 76. A pawl 157 provided with a handle 157' is pivoted to the bar and adapted to engage a shoulder 158 formed on the standard 73 to support the arm-engaging portion 156 in an elevated position to hold the arm 76 aslant at one angle. By withdrawing the pawl from the shoulder the bar is allowed to slip down the standard until caught by the supporting hook 155', thereby allowing the rock 100 105 110 115 120 125 130

shaft arm 76 to drop to a different angle with the path of the crank-pin 24. When the rock shaft arm is supported in its upper position the crank shaft escapes from the arm after moving the arm through a limited arc, but when the rock shaft arm is unsupported by said portion, the crank pin 24 will reach said arm earlier and move it through a greater arc. The action of the driving pawl 86 is proportionately greater or less, depending on whether the rock shaft arm 76 is supported at the lower or upper position.

In the machine illustrated there are fifty-three teeth in the driving ratchet wheel 87 so that when the rock shaft operates the driving pawl 86 only one notch at a time, the bar will be cut into fifty-two transverse slices of two chips each, and the fifty-third tooth will operate to move the plunger forward one step beyond the position where the filose cutter was when the last chip was released. This additional step is necessary in order to advance the plunger to a point where the rack is free from the mutilated gear; and when this point is reached, the spiral retracting spring 105 immediately retracts the plunger; and the escapement being released on the return of the plunger, the inner limbs of the sprocket chains are allowed to descend, thus bringing a new butter bar into position in front of the plunger and dropping the empty butter bar tray to the floor of the machine from whence it may be removed by opening the lower door 159 in the front of the machine.

When it is desired to increase the thickness of the butter chips the bearing 155 is lowered, so that the rock shaft arm 76 will be moved twice the arc in which it was previously moved; and when thus adjusted the driving pawl is retracted two notches instead of one at each operation of the rock shaft and on its return by the spring 90 the lever 91 will operate the driving pawl through the space occupied by two ratchet teeth, thus turning the mutilated gear twice as far as before and thereby advancing the plunger a like distance.

When the plunger has been advanced to the filose cutter it is desirable that the next step which releases the plunger rack from the mutilated gear shall only equal the space between the fifty-third tooth and the one immediately following; and to allow the machine to be fully adjusted to make the thicker chips, an adjustable runner 160 is pivoted to the ratchet wheel 87 and clamped thereto by the slot and screw connection 161, 162 (see Fig. 17) so that by fixing the runner in place to close the space between the first two teeth the pawl is supported against dropping therebetween.

The operation of the apparatus will be understood from the foregoing. The ap-

paratus may be charged with butter bars by opening the front door 4 and inserting the trays onto the brackets and placing the butter bars on the trays. The butter bars may be stored in the ice chest, the top of the case being removable for that purpose, and the operator will use his judgment as to how many butter bars will be placed in the machine at a time, it being preferable to leave the butter bar and its tray in the ice chest until the demand for it arises, but it is understood that where the demand will be rapid, a larger number of trays with butter bars thereon will be placed on the brackets than when the demand is expected to be limited. When the machine is thus charged, the plunger, being fully retracted, the waiter will place a butter plate centrally on the shelf 71 and will then operate the crank lever twice, thus bringing the filose cutter to a stop centrally in front of the butter bar and advancing the butter bar at the close of the second movement to slit it by forcing its end past the filose cutter. At the next movement of the crank lever a chip will be cut and ejected onto the butter plate. If two chips are desired, the crank will be operated again, thus depositing another chip on the butter plate. At the end of this movement, the plunger is kicked forward by the actuating spring 90. As the work goes on the plunger is advanced after each second cutting until the last chip is ejected and the plunger rack has reached the open segment of the mutilated gear, whereupon the retracting spring retracts the plunger and the tripper 146 actuates the escapement lever thus releasing the escapement wheel and allowing the weight of the butter bars on the sprocket chains to move said sprocket chains, thus withdrawing the lower brackets from the empty tray and allowing such tray to drop to the floor and the next filled tray to go into position on a level with the filose cutter, after which the operation proceeds as hereinbefore described.

If it is found in case of very hard butter that the spring 90 does not act with sufficient force to drive the butter bar so as to cut it with the filose cutter, the tension of said spring may be increased by screwing down the tension nut 95, and vice versa; the nut will be loosened if the butter bar is softer.

I claim:—

1. The combination with a butter bar support, of a slide provided with an orifice, a filose cutter carried by the slide at the center of the orifice, means to advance the butter bar on the support, and mechanism to alternately move the slide from central position to one side and back and vice versa.

2. Butter cutter mechanism comprising a transverse slide provided at one side with a vertical slot, a crank the pin of which is in

the slot, means to operate the crank by half turns to move the slide in one and the other direction, and a filose cutter carried by the slide.

5 3. The combination with a slide provided with a slot, of a filose cutter carried by the slide, and a crank pin in the slot, said slot being equal in length to the diameter of the path of the crank pin, so that a complete cycle of the slide is effected at each revolution of the pin.

15 4. The combination with a slide provided with a slot, of a filose cutter carried by the slide, a crank pin in the slot, said slot being equal in length to the diameter of the path of the crank pin, so that a complete cycle of the slide is effected at each revolution of the pin, and stops to stop the slide at the close of each half revolution.

20 5. The combination with a filose cutter,
of a slide carrying said cutter and arranged
to normally stand at rest with the filose cutter
in a vertical plane, mechanism to ad-
vance a butter bar step by step against the
25 filose cutter one step for each cycle of the
slide, and means to alternately move the
slide from its central point of rest to one
side and back to rest and then from said
point of rest to the other side and back to
30 rest.

6. The combination of a slide provided with an orifice, a filose cutter across the orifice, a crank, means connecting the crank with the slide to operate the slide from center to side and back to center alternately on opposite sides of the center, and means to advance a butter bar through said orifice.

40 7. A butter cutting apparatus comprising
mechanism for holding and advancing a
butter bar, a filose cutter, means for holding
the filose cutter centrally of the butter bar
while said bar is being advanced, and means
for moving the filose cutter to one and the
45 other side of the central position, and vice
versa, while the bar is held stationary so
as to cut two chips of butter from the end
of the bar between each two advancing
movements.

50 8. The combination of mechanism for holding and advancing a butter bar; mechanism including a filose cutter and means for moving the same to and fro, to cut the bar into chips; mechanism for automatically stopping the filose cutter centrally before said butter bar holding mechanism, between the cutting strokes; and mechanism for ejecting the butter chips.

9. The combination with a filose cutter
60 and a butter bar holder, of means to move
the cutter laterally for cutting a butter bar
transversely; mechanism for automatically
stopping the cutter centrally in front of
the butter bar between the cutter strokes;
65 mechanism for ejecting butter chips; mech-

anism for actuating the ejecting mechanism; mechanism for advancing the butter bar; mechanism for connecting the cutter and ejector actuating mechanisms with the butter bar advancing mechanism; mechanism for supporting butter bars and moving them successively into position for coöperation with the bar advancing mechanism; and mechanism for regulating the thickness of the butter chips. 75 70

10. In a butter dispenser the combination with a case having a central front opening, abutments provided with lips adapted to extend into said opening, means behind the abutments to support a butter bar, and means to move the butter bar on said support into the space between the abutments. 80

11. In a butter dispenser the combination with a case having a central front section provided with an opening, abutments provided with lips adapted to extend into said opening, means behind the abutments to support a butter bar, means to move the butter bar on said support into the abutments, a filose cutter adjacent to the abutments, and means to move said filose cutter transversely of the support. 85 90

12. In a butter dispenser the combination with a case having a central front opening, slotted slides provided with abutments 95 adapted to extend into said opening, adjusting screws extending through the slots into the case to adjustably hold the abutments, means behind the abutments to support a butter bar, and means to move the 100 butter bar on said support into the abutments.

13. In a butter dispenser the combination with a case having a central front section provided with an opening, slotted slides provided with abutments adapted to extend into said opening, adjusting screws extending through the slots into the case to adjustably hold the abutments, means behind the abutments to support a butter bar, means to move the butter bar on said support into the abutments, a filose cutter between the abutments, and means to move said filose cutter transversely of the support. 105 110

14. The combination with a case having
an intermediate hinged front section pro-
vided with an opening, a filose cutter, a slide
carrying the filose cutter and adapted to
move said cutter adjacent said opening, a
stub shaft journaled in the hinged section,
a crank fixed on the inner end of said stub
shaft and having a crank pin, a collar se-
cured upon the outer end of the stub shaft
and provided on opposite sides of its axis
with ratchet teeth adapted to be successively
engaged by a spring controlled pawl, such
pawl, an operating lever carrying said pawl
and that is hand-operated in one direction
and spring returned in the opposite direc-
tion, a spring for returning the crank, a
115
120
125
130

stop to stop the operating lever at rest position, said slide being provided with a vertical slot in which the crank pin operates.

15. In a butter dispensing apparatus, a case for the mechanism of said apparatus, said case being provided with an opening through which the butter chips may be ejected and a hood over said opening, said hood being open at its under side below the level of the case opening; and refrigerating means inside the case.

16. An automatic butter dispenser having means for cutting a bar comprising a filose cutter, means to reciprocate said cutter, and means to advance the bar upon said cutter at its central position to cut the bar longitudinally.

17. An automatic butter dispenser having filose cutter means for cutting bar material, means to supply said bar material to the cutter means, and means for ejecting the cut portions from the cutters.

18. In an automatic butter dispenser, a reciprocating slide provided with a filose cutter, means to supply bar material to the cutter, means to alternately reciprocate said cutter upon each side of a normal mid-position thereof, an ejector to eject cut portions, and means upon the slide to actuate the ejector to coöperate with the cutter at each of said alternate reciprocations.

19. In an automatic butter dispenser, a reciprocating slide, a filose cutter carried by the slide, means to supply bar material to the cutter, means to alternately reciprocate said cutter upon each side of a normal mid-position thereof to constitute a cutting and retracting stroke, an ejector slidably and rotatively mounted adjacent to the cutter, and means upon the slide to reciprocate the ejector simultaneously with said cutter and to partially rotate the same at the completion of each cutting stroke.

20. In an automatic butter dispenser, a reciprocating slide, a filose cutter carried by the slide, means to supply bar material to the cutter, means to alternately reciprocate said cutter upon each side of a normal mid-position thereof to constitute a cutting and retracting stroke, stops adjacent to and in front of the cutter, an ejector slidably and rotatively mounted between said stops, said ejector being provided with an arm, and means upon the slide to move the ejector to alternately engage the stops to thereby cause the arm to swing outwardly at the completion of the cutting stroke of each of said alternate reciprocations.

21. In an automatic butter dispenser, a reciprocating slide, a filose cutter carried by the slide, means to supply bar material to the cutter, means to alternately reciprocate said cutter upon each side of a normal mid-position thereof to constitute a cutting and retracting stroke, stops adjacent to and in

front of the cutter, an ejector slidably and rotatively mounted between said stops, said ejector being provided with an arm and an actuating pin, and means upon the slide to act upon the actuating pin to move the ejector to alternately engage the stops to thereby cause the arm to swing outwardly at the completion of the cutting stroke of each of said alternate reciprocations.

22. In an automatic butter dispenser, a reciprocating slide, a filose cutter carried by the slide, means to supply bar material to the cutter, and means to alternately reciprocate said slide upon each side of a normal mid-position thereof to thereby operate the cutter.

23. In an automatic butter cutter, a reciprocating slide provided with a filose cutter, means to supply bar material to the cutter, means to alternately reciprocate said cutter upon each side of a normal mid-position thereof, and automatic stop means to stop the slide with the cutter at its normal mid-position.

24. In an automatic butter cutter, a reciprocating slide provided with a filose cutter, means to supply bar material to the cutter, means to alternately reciprocate said cutter upon each side of a normal mid-position thereof, automatic stop means to stop the slide with the cutter at its normal mid-position, and automatic means to release said stop means.

25. In an automatic butter cutter, a reciprocating slide provided with a filose cutter, means to supply bar material to the cutter, means to alternately reciprocate said cutter upon each side of a normal mid-position thereof, automatic stop means to stop the slide with the cutter at its normal mid-position after reciprocating said cutter upon one side of said mid-position, and automatic means to release said stop means to allow reciprocation upon the other side of said mid-position.

26. In an automatic butter cutter, a reciprocating slide having a filose cutter mounted thereon, means to supply bar material to the cutter, a crank mounted to alternately reciprocate said slide upon each side of a normal mid-position thereof, and an operating lever to actuate the crank.

27. In an automatic butter cutter, a reciprocating slide having a filose cutter mounted thereon, means to supply bar material to the cutter, a crank mounted to alternately reciprocate said slide upon each side of a normal mid-position thereof, crank stop means to stop the slide at its normal mid-position, and an operating lever to actuate the crank and release the crank stop means.

28. In an automatic butter cutter, a reciprocating slide having a filose cutter mounted thereon, means to supply bar ma-

terial to the cutter, a crank mounted to alternately reciprocate said slide upon each side of a normal mid-position thereof, crank stop means to stop the slide and cutter at their normal mid-position, and an operating lever adapted to turn the crank upon an actuating stroke and to release the crank stop means upon a retracting stroke.

29. A butter dispenser comprising a case 10 having in the front a hinged section; mechanism inside the case to supply butter to be cut; and butter cutting mechanism mounted on said section, and adapted to coöperate with the butter supplying mechanism when 15 the section is in closed position and to expose the butter supplying mechanism when the section is open.

30. The combination with a butter bar 20 holder, of means to move a bar along the holder step by step, means to cut chips from one and the other sides of the end of the bar; and an ejector to eject the chips as they are severed from the bar.

31. The combination with a cutter, of 25 means to supply a bar of butter to the cutter; a slide to carry the cutter; a crank lever; a stop for the crank lever; a spring to yieldingly hold the crank lever against the stop; a stub shaft; a frame to which the 30 stub shaft is journaled; a crank on the stub shaft; means connecting the crank lever with the stub shaft to turn said shaft step by step, said crank being arranged to move the slide step by step, and mechanism connecting the crank with the butter-supplying 35 means.

32. The combination with a slide; of a cutter carried by the slide, said slide being provided with a slot extending in parallelism with the cutter; a crank working in the slot, a crank lever operatable by a half turn to move the crank a half turn at a time; a cam connected with said crank lever, a rock shaft operatable by the cam at the 45 close of the return movement of the crank lever; a pawl operated by the crank lever and arranged to move the crank step by step, bars operatively connected with the rock shaft and arranged to stop the crank at the 50 end of each step, said cam being arranged to move the bars out of the way of the crank at the close of the return movement of the crank lever.

33. The combination with a cutter; of a 55 slide carrying the cutter and provided with a slot in parallelism with the cutter; a crank having a pin in the slot; a crank lever connected by a ratchet mechanism to turn the crank step by step by half revolutions 60 of the crank; means to return the crank lever; a stop to stop the crank lever on its return; a cam revoluble with the crank lever; a rock shaft having an arm operated by the cam at the close of the return movement of the cam lever; a bar connected with

the rock shaft and arranged to stop the crank at one point of its movement; a bar arranged to stop the crank at an opposite point of its movement; and a connecting rod connected at one end to one of the bars between its pivotal point and the stop face of such bar that engages the crank pin, and connected at its other end eccentrically to the rock shaft on the side thereof opposite the other bar.

34. The combination with a cutter; of a slide carrying the cutter, said slide being provided with a transverse slot; a crank the pin of which works in the slot; a crank lever; ratchet mechanism between the crank lever and the crank to rotate the crank by half revolutions of the crank lever; a cam connected with the crank lever, a rock shaft provided with an arm actuated by the cam; a bar mounted near one of its ends on the rock shaft and provided near the other end with a stop face to stop the crank pin at one point of its revolution; a pivoted bar provided with a stop face to stop the crank pin at the opposite point of its revolution; and a connecting rod connecting the short arm of the first-named bar with the other bar between the pivot and the stop face of said other bar; the weight of the cam-actuated arm and the connecting rod being sufficient to normally hold the stop faces in the path of the crank pin; the said cam being arranged to move the stop faces out of the path of the crank pin at the close of the return movement of the crank lever.

35. The combination with a slide; of a cutter carried by the slide; means to reciprocate the slide and cutter; a guide-rod extending in parallelism with the way of the cutter; stops; a sleeve slidably and rotatably mounted on said guide and between the stops; an actuating pin on the sleeve; an ejecting finger on the sleeve; actuating tappets provided with downwardly diverging faces and horizontal slots; screws in said slots and adjustably connecting the tappets with the slide; said actuating pin extending between said faces; a spring in the form of a spiral loop bent around the sleeve, one end of the spring being under the actuating pin and the other looped end resting against the slide, so that the upper pressure of the spring on the pin retracts the ejecting finger and yieldingly holds the tip of the ejecting finger in a transverse plane that extends just in front of the cutter; and means to reciprocate the slide.

36. The combination with a slide; of a cutter carried by the slide; a guide-rod extending in parallelism with the way of the cutter; stops; a sleeve slidably and rotatably mounted on said guide rod between the stops; an actuating pin on the sleeve; an ejecting finger on the sleeve; actuating tappets on the slide provided with downwardly

diverging faces; said actuating pin extending between the faces; a spring in the form of a spiral loop bent around the ejector sleeve, one end of the spring being under the 5 actuating pin and the other being looped and resting against the slide, so that the upper pressure of the spring on the pin retracts the ejecting finger yieldingly holding the tip of the ejecting finger in a transverse 10 plane extending just in front of the cutter; and means to reciprocate the slide.

37. The combination with a slide; of a cutter carried by the slide; a guide-rod in parallelism with the slide; a sleeve mounted 15 on the guide-rod; an ejector finger fixed to the sleeve; an actuating tappet on the slide; means whereby the tappet moves the sleeve with lost motion in the direction in which the slide moves; stops for the sleeve to hold 20 the sleeve while the tappet moves the same; and means to operate the slide.

38. The combination with a slide; of a cutter carried by the slide; a guide-rod in parallelism with the slide; a sleeve mounted 25 on the guide-rod; an ejector finger fixed to the sleeve; an inclined actuating tappet on the slide; means whereby the tappet moves the sleeve with lost motion in the direction in which the slide moves; stops for the sleeve 30 to hold the sleeve whereby the inclined tappet may give rotary motion to the same; means to operate the slide; and means to rotate the sleeve to retract the ejector finger when the sleeve is freed from the tappet.

35 39. The combination with a filose cutter and means to reciprocate the cutter; of an ejector finger having a tip and movable in parallelism with the cutter; means to move the ejector finger away from the plane in 40 which the cutter travels; and means to practically return the tip of the finger to the plane of the cutter.

40. The chip ejector for a butter dispenser substantially as set forth comprising 45 an ejector finger having a vertical tip; a sleeve carrying said finger; and means for moving the sleeve in parallelism with the cutter and for revolving the sleeve to operate the finger.

50 41. The combination with a filose cutter; of means to move a butter bar toward the cutter; means to move the cutter transversely of the butter bar, an ejector finger, and means to operate the ejector finger to 55 eject the butter chip cut by the cutter.

42. In a butter cutter a slide having an orifice; a wire stretched across the orifice; means to tighten the wire; an ejector finger having a vertical tip movable into and from 60 the path of the wire; and means movable with the slide to actuate the ejector to move the vertical tip to eject a butter chip severed by the wire.

43. In a butter dispenser a butter cutter; a chip ejector; butter bar advancing 65

mechanism; actuating mechanism for the chip ejector; a crank lever operatively connected with the butter cutter and with the advancing mechanism; and means connecting said actuating mechanism with the butter cutter for successive operations substantially as set forth. 70

44. The combination with a filose cutter and means to move the cutter to chip butter from the end of a butter bar, of means 75 to move a butter bar toward the cutter to divide the end of the bar into two parts preparatory to forming two chips when the cutter is operated; and a movable ejector to eject the chips. 80

45. The combination with a slide, of a cutter carried by the slide, an ejector in movable relation to the slide and tappets adjustable on the slide to actuate the ejector. 85

46. The combination with a cutter, of a slide carrying the cutter and provided with a transverse slot, a crank provided with a crank pin in said slot to operate the slide, a rock shaft having two arms, one arm of said rock shaft being operable by the crank to 90 turn and to suddenly release the rock shaft, a pivoted lever, a connecting rod connecting the other rock shaft arm with the pivoted lever, a driving shaft, a ratchet arm journaled on the driving shaft, a connecting rod 95 connecting the other end of said pivoted lever with the ratchet arm, a driving pawl on the ratchet arm, a ratchet wheel engaged by said pawl and fixed on said shaft, a locking pawl to prevent back movement of the 100 ratchet wheel, a spring, a driving lever operable by the pivoted lever to compress the spring when said pivoted lever is actuated to retract the driving pawl and adapted to be operated by the spring and to actuate the pivoted lever when the rock-shaft arm escapes the crank. 105

47. The combination with a cutter, of a slide carrying the cutter, a crank to operate the slide, a rock shaft having two arms, one arm of said rock shaft being operable by the crank to turn and to suddenly release the rock-shaft, a plunger to move a butter bar toward the cutter, a spring, means operable by the rock shaft to compress and suddenly release the spring, and means operable by the spring to advance the plunger. 110 115

48. The combination with a cutter, of a plunger to move a butter bar toward the cutter, a spring, means to compress the spring, and means operable by the spring to advance the plunger. 120

49. The combination with a cutter, of a plunger, lever and ratchet mechanism connected to operate the plunger to move a butter bar toward the cutter, a spring to actuate said lever and ratchet mechanism, and means to compress and release the spring. 125

50. The combination with a cutter, of a 130

plunger, lever and ratchet mechanism connected to operate the plunger to move a butter bar toward the cutter, a spring to actuate said lever and ratchet mechanism, and 5 mechanism to reciprocate the cutter and to compress and release the spring.

51. The combination with a butter bar support, of a cutter in front of said support, mechanism to move a butter bar along said 10 support toward said cutter, a driving lever, a spring to move the lever in one direction, a pivotally mounted lever arranged to operate the driving lever against the force of the spring and to be operated by said driving 15 lever when actuated by the spring, and ratchet mechanism connected with said pivotally mounted lever to drive the butter bar moving mechanism.

52. In a butter cutter the combination 20 with a butter bar support and a plunger to move the butter bar along said support, of mechanism to advance the plunger, ratchet mechanism connected to drive the plunger advancing mechanism, means to retract said 25 ratchet mechanism, and a spring compressed and released by said ratchet retracting mechanism to drive said ratchet mechanism and the plunger.

53. The combination with ratchet mechanism, of a pivoted lever connected with the 30 ratchet mechanism, means to operate the pivoted lever to actuate the ratchet mechanism, a spring, a driving lever actuated by the spring to operate the pivoted lever, thereby to operate the ratchet mechanism 35 and operable by said pivoted lever to compress the spring, a support for a butter bar, and a plunger operated by the ratchet mechanism to move the butter bar along the 40 support.

54. The combination with a support for a butter bar and means to move the butter bar along said support, of a rack to operate said means, a mutilated gear comprising a toothed 45 segment and a blank segment, the toothed segment meshing with the gear and being of sufficient length to move the plunger one step beyond the cutter, the blank segment of said mutilated gear being of sufficient 50 length to disengage the rack and allow it to run back at each revolution of said gear.

55. The combination with a cutter, and a butter bar support, of means to move a butter bar along said support toward the cutter, comprising a mutilated gear, means to drive said mutilated gear, a catch on the mutilated gear, a latch to engage the catch, means including a lock-pawl to hold the mutilated gear from back action, a rack actuated by the mutilated gear, a tripper to retract the latch when the rack is fully retracted, and a rack-starter fixed to and revolving with the mutilated gear and adapted to engage the rack and to advance the 65 same when the tripper has released the

latch, so that on the next forward movement of the pawl the rack will be advanced to engage the toothed segment of the mutilated gear.

56. The combination with a plunger to advance a butter bar, of a butter bar support below said plunger, mechanism carrying said support, mechanism to advance and return the plunger, and mechanism to lower the support when the butter bar advancing 70 mechanism is retracted.

57. The combination with a cutter and means to operate the same, of a butter bar support, a plunger operable along said support to advance a butter bar toward the 80 cutter, mechanism to advance the plunger and a spring to retract the plunger.

58. The combination with a cutter, of a butter-bar support, a slide-way slotted longitudinally with parallel slots and with an 85 stub shaft journaled in the auxiliary slide mounted on the slide-way, a plunger slide mounted on the auxiliary slide, a rack carried by the plunger slide, said plunger slide being provided with parallel slide slots and an intermediate toothed slot, the teeth of one intermediate slot being on one side of their slot and the teeth of the other intermediate slot being on the other side of their slot, and a stub shaft journaled in the auxiliary slide 90 and provided with pinions to engage the teeth of the intermediate slots respectively, so that as the plunger slide is advanced the auxiliary slide is advanced at half speed and vice versa upon retraction to operate 100 the auxiliary slide to support the plunger when it is moved in the way of the butter bar.

59. The combination with a cutter, of sprocket wheels, sprocket chains mounted on said sprocket wheels, brackets on the sprocket chains, butter bar supporting trays on the brackets, means connecting the sprocket wheels to cause them to rotate at a common speed, an escapement wheel to control said sprocket wheels, said escapement wheel being provided at intervals with teeth, a pivoted escapement lever, a spring by which said lever is normally held in the way of said teeth to support the escapement 110 wheel against the weight upon the brackets, means to advance a butter bar along one of the trays toward the cutter, means to return the butter bar advancing mechanism, and means operated by the return of said butter bar advancing mechanism to withdraw the escapement lever from the escapement wheel and allow the sprocket wheels to turn.

60. The combination with a cutter, of 125 sprocket wheels, sprocket chains mounted on said sprocket wheels, brackets on the sprocket chains, butter bar supporting trays on the brackets, means connecting the sprocket wheels to cause them to rotate at 130

a common speed, an escapement wheel to control said sprocket wheels, said escapement wheel being provided at intervals with teeth, a pivoted escapement lever, a spring 5 by which said lever is normally held in the way of said teeth to support the escapement wheel against the weight upon the brackets, means to advance a butter bar along one of the trays toward the cutter, means to return 10 the butter bar advancing mechanism, and means operated by the return of said butter bar advancing mechanism to withdraw the escapement lever from the escapement wheel and allow the sprocket wheels to turn; said 15 escapement being arranged to stop the sprocket wheels from turning when they have moved just the space between two trays.

61. The combination with a cutter, of sprocket chains provided with brackets, 20 trays supported by said brackets, mechanism to connect said sprocket chains, escapement mechanism to hold the chains from turning, said mechanism being provided with an escapement lever, mechanism to advance the 25 butter bar along a tray, means to return said butter bar advancing mechanism, and means operated on the return of said butter bar advancing mechanism to release the escapement lever.

62. The combination with a cutter of trays 30 adapted to support butter bars, means to support the trays at and above the level of the cutter, mechanism to advance a butter bar along the tray at the level of the cutter, 35 means to retract said mechanism, and means releasable on the retraction of said mechanism to allow the trays to descend.

63. The combination with a filose cutter 40 of brackets, sprocket chains to support the brackets at the level and above the level of the filose cutter, said brackets being arranged on the sprocket chains in position to be stopped respectively when in position to support a tray on a level with the filose 45 cutter, a plunger movable along such tray to advance the butter bar toward the filose cutter, means to retract the butter bar advancing means, means to allow the sprocket chains and brackets to move to discharge 50 the empty tray, and means to stop the chain

in position with the brackets to hold the next tray at the level of the filose cutter.

64. The combination with a filose cutter, of a tray formed of a plate and having ears bent up at its rear end to hold the rear end 55 of a butter bar and provided with butter bar guides at the front end to direct a butter bar into the path of the filose cutter, means to move the filose cutter transversely of the tray, and means to move the butter bar toward the filose cutter.

65. The combination with a filose cutter, of a tray, guides on the tray, said guides being pivoted on the tray and provided with inter-meshing segments so that the guides 65 in all positions are spread apart at an equal distance from the longitudinal mid-line of the plate, and means to move the butter bar between said guides toward the filose cutter.

66. The combination with a filose cutter, 70 means to support a butter bar at the level of said cutter, mechanism to advance the butter bar toward said cutter, a rock shaft having an arm, mechanism operated by the rock shaft to actuate the butter bar advancing mechanism, means operable in time with the filose cutter to actuate said arm and shaft, and means to adjust the arm with relation to said actuating means, thus regulating the length of the movement which operates the butter bar advancing mechanism.

67. In a butter dispensing device the combination with a filose cutter, of means to move the cutter, means to support a butter bar at the level of the cutter, butter bar advancing mechanism, ratchet mechanism for operating the butter bar advancing mechanism, a rock shaft, mechanism operated by the rock shaft to actuate the ratchet mechanism, and means for regulating the movement of the rock shaft relative to a cycle of the cutter.

In testimony whereof, I have hereunto set my hand at Los Angeles, California, this 31st day of August, 1912.

EDWIN M. LARSON.
